UNITED STATES PATENT OFFICE.

ISAAC GOLDSSTONE, OF BROOKLYN, NEW YORK.

SANDAL.

1,250,852.

Specification of Letters Patent. Patented Dec. 18, 1917.

Application filed October 8, 1917. Serial No. 195,447.

To all whom it may concern:

Be it known that I, ISAAC GOLDSSTONE, a citizen of the United States, and a resident of the city of New York, borough of 5 Brooklyn, in the county of Kings and State of New York, have invented a new and Improved Sandal, of which the following is a full, clear, and exact description.

My invention relates to sandals having 10 soles of rigid material and the object is to render such a sandal comfortable by forming said sole of relatively movable sections.

With the above and other objects in view, the nature of which will more fully appear 15 as the description proceeds, the invention consists in the novel construction, combination and arrangement of parts as herein fully described, illustrated and claimed.

In the accompanying drawings, forming 20 part of the application, similar characters of reference indicate corresponding parts in all the views.

Figure 1 is a side elevation of a sandal embodying my invention;

25 Fig. 2 is a front end elevation of the sandal in use;

Fig. 3 is a fragmentary bottom plan view of the sole of the sandal; and

Fig. 4 is a fragmentary section through 30 the sole of the sandal.

Referring to the drawings, the sole 5 is formed of two sections 6 and 7 hinged together substantially at the ball part of the foot, 6 being the rear section and 7 the 35 front section. The hinge is preferably formed of a flexible member 8 running transversely of the sole and secured to the sections 6 and 7 by means of a thread 9.

The sections are preferably recessed to accommodate the flexible member 8, to render 40 the inner surface of the sole smooth for the foot. The sections are also recessed on the bottom or wearing surface, as shown at 10, so that the thread securing the flexible member 8 forming the hinge will not wear. 45

To prevent sand from interfering with the relative movement of the sections 6 and 7, these sections are rounded at the meeting edges so that the distance between the 50 sections increases toward the wearing surface, as indicated at 11. In consequence the relative movement of the sections tends to squeeze out therebetween any matter that may enter.

The flexible member 8 forming the hinge 55 is preferably extended beyond the edges of the sole so that the ends 12 of said flexible member may be folded about the foot resting on the sole for the purpose of receiving a tying lace 13. For that purpose the extremities of said flexible members are looped, as shown at 14, so that the lace may be threaded therethrough.

The rear section 6 is provided with a rear strap 15 provided with a loop 16 at its 65 free end through which the lace is threaded. In addition the rear section has side strips 17 also provided with loops 18 at the free end for engaging the lace 13. The side strips are preferably placed in proximity 70 to the heel portion so that with the rear strap the sole can be firmly secured to the rear part of the foot. The front section 7 has at the free end thereof a front strap 19 provided with a loop 20 at its upper end 75 through which the lace 13 is threaded. By means of this strap the front or extreme end of the sole is secured to the toes of the foot. It will be noted that a single lace is used for tying the sandal to the foot. This lace permits ample relative movement between the sections 6 and 7 during walking.

The relatively movable sections 6 and 7 of the sole 5 permit comfortable walking over uneven ground without fatigue to the 85 foot, as the relative motion is provided at a point where the foot has a natural tendency to bend.

While I have described the principle of operation, together with the device which 90 I now consider to be the best embodiment thereof, I desire to have it understood that the device shown is merely illustrative and that such changes may be made as are within the scope of the appended claims.

I claim:

1. In a sandal, a sole of rigid material formed of a front section and a rear section, a flexible member uniting said sections together, said flexible member extending beyond the edges of the sole sections, and a lace for tying the flexible member about the foot.

2. In a sandal, a sole of rigid material formed of a front section and a rear section, 105 a flexible member uniting the sections together, said flexible member having extensions adapted to engage a foot, straps asso-

ciated with the two sections for engaging a foot, and a lace engaging said straps and extensions for tying the same about the foot.

3. In a sandal, a sole of rigid material
5 formed of a front section and a rear section, the meeting edges of the two sections being substantially where the ball of the foot is adapted to bear on the sole, a flexible member uniting said sections together, said
10 sections being recessed to receive the flexible member so as to present a flat unobstructed surface to the foot, said flexible member extending beyond the sides of the sole to fold about the foot resting on the sole, straps
15 associated with the sections, and a lace engaging said straps and flexible member for tying the same to the foot on the sole, the

meeting edges of the sections being rounded to diverge toward the wearing surface of the sole.

4. In a sandal, a sole of rigid material formed of a pair of sections, a flexible member hinging said sections together and disposed transversely of the sole, said sections being recessed to receive said flexible member, each of said sections having a recess on the wearing surface below the recess for the flexible member, and means securing said flexible member to the sections and adapted to engage said recesses on the wearing surface of the sections, the facing edges of said sections being rounded to diverge toward the wearing surface of the sole.

ISAAC GOLDSTONE.
